UNITED STATES PATENT OFFICE.

DAVID D. BUICK, OF DETROIT, MICHIGAN.

DESIGN FOR A FAUCET.

SPECIFICATION forming part of Design No. 29,705, dated November 22, 1898.

Application filed October 14, 1898. Serial No. 693,568. Term of patent 14 years.

To all whom it may concern:

Be it known that I, DAVID D. BUICK, a citizen of the United States, residing at Detroit, in the county of Wayne and State of Michigan, ⁵ have invented and produced a new and original Design for a Faucet, of which the following is a specification, reference being had therein to the accompanying drawings.

Figure 1 is a front elevation. Fig. 2 is a ¹⁰ perspective view.

A A are two parallel cylindrical standards connected at their upper ends by the upwardly-curved yoke B, from the center of which extends the outwardly and downwardly ¹⁵ curved nozzle C.

D is an urn extending upward from the center of the yoke.

E are polygonal enlargements between the yoke and standards.

G are enlargements in each of the standards, between the base thereof and the polygonal section.

The leading feature of my design consists in the parallel standards connected by the upwardly - curved yoke having the curved ²⁵ nozzle extending outward and downward centrally from said yoke.

What I claim as my invention is—

The design for a faucet as herein described and shown.

In testimony whereof I affix my signature ³⁰ in presence of two witnesses.

DAVID D. BUICK.
